Fig. 7

Fig. 8

Fig. 9Fig. 10Fig. 11Fig. 12

FIG. 1 is a top plan view of a water scooter showing my new design;

FIG. 2 is a side elevational view thereof;

FIG. 3 is a bottom plan view thereof;

FIG. 4 is a rear view thereof;

FIG. 5 is a top plan view of a second embodiment of a water scooter showing my new design;

FIG. 6 is a side elevational view thereof;

FIG. 7 is a bottom plan view thereof;

FIG. 8 is a rear view thereof;

FIG. 9 is a top plan view of a third embodiment of a water scooter showing my new design;

FIG. 10 is a side elevational view thereof;

FIG. 11 is a bottom plan view thereof; and

FIG. 12 is a rear view thereof.

The rope shown fragmentarily in FIGS. 1, 2, 3, 5, 6, 7, 9, 10 and 11, is shown to indicate indeterminate length.

1 claim:

The ornamental design for the water scooters, as shown and described.
